(57) CLAIM

The ornamental design for a kitchen vessel handle, as shown and described.

DESCRIPTION

FIG. 1 is a top plan view of a kitchen vessel handle according to the design of my invention;

FIG. 2 is a side elevational view thereof, the opposite side being a mirror image;

FIG. 3 is a front elevational view thereof;

FIG. 4 is a rear elevational view thereof; and,

FIG. 5 is a bottom plan view thereof.

The dashed lines are for environmental purposes and form no part of this design
